TYPOGRAPHICAL COMPOSING MACHINE

Christian Augustus Albrecht, Berlin, Germany,
assignor to Mergenthaler Linotype Company,
Brooklyn, N. Y., a company of New York

Application November 30, 1936, Serial No. 113,386
In Germany June 20, 1936

7 Claims. (Cl. 199—45)

This invention relates to typographical composing machines.

In such machines having a plurality of magazines arranged in superposed relation as a column, it is usual to employ matrix entrance channels (hereinafter called magazine entrances) capable of being interchanged and which, when the magazines are shifted are changed one for another by axial rotation. Such change-over is effected at the same time as the shifting movement of the magazines, so that the rotation and the change-over of the entrances is performed at every magazine shifting operation. Such means are therefore only applicable to machines where-in a change-over of the magazine entrances is necessary each time the magazines are shifted. In order to allow application of this automatic rotary change-over of the magazine entrances to a particular magazine arrangement, it has been proposed, when using a rack bar and pinion mechanism for the rotary change-over, to make the rack bar interchangeable and to fit it to the magazine arrangement in use for the time being. This arrangement makes it necessary however to have different rack bars always available and to interchange them when required.

The object of the invention is to overcome these disadvantages in the known arrangements, and to make the rotary change-over of the magazine entrance entirely independent of the magazine change. According to one embodiment of the invention the locking and the change-over of the magazine entrances, joined together into a rotatable unit, is effected by the movement of a handle, operating the release of the magazine shift, beyond the extent required for releasing the magazines.

In the drawings, one constructional form of the invention is illustrated by way of example, and in the said drawings:—

Figure 1 is a diagrammatic side elevation of the relevant parts of a matrix composing and line casting machine according to the invention;

Figure 2 shows, on a larger scale, the magazine entrances together with the pertinent change-over and locking mechanism in the operative position;

Figure 3 is a part of Figure 2 and shows the parts after their release, and

Figure 4 is the same illustration as Figure 3, but showing the said parts after the change-over.

In the construction illustrated in the drawings, 1 is the machine frame, and 2 the magazine

column, consisting of any desired number of magazines (four being shown in the construction exemplified) which are supported by a suitable frame. The magazine column is guided in the usual manner by means not illustrated in the drawings, so that it can be moved upwardly and downwardly, perpendicularly to its top and bottom plates. In order to shift the magazine column, rack bars 3 are articulated to it, and preferably to the base frame. The rack bars mesh with toothed gears 4, upon the shaft of which are secured bevel gears 5 in mesh with bevel gears 6 mounted on a shaft 7, and the shaft 7 carries a handle 8 so that by turning the handle, the magazines will be adjusted to different levels. 10 When changing over from one magazine to another, it is necessary for the shaft 7 to be turned to a certain extent, (preferably to the extent of one whole revolution for changing from one magazine to the next), and in order to be able to lock the shifting frame after each shifting operation, a disc 9 is mounted upon the shaft 7 and carries on its periphery a notch, in which engages a ledge 10 mounted on a lever 12 adapted to swing about a stud 11 on the magazine frame. 15 Upon a pivot 13 is located a three-armed lever, one arm 14 of which is formed as a handle, the second arm 15 is articulated to a draw-rod 16, and third arm 17 consists of a segmental portion, which is adapted to bear against a roller 18 mounted on the lever 12. The lever 12 is also provided with a cam 19 serving to move a lever 20, fitted with a roller, which is loosely mounted on the shaft 13 and serves to rock the releasing rods 21 which operate the release of the matrices 20 from the magazine, but which must be moved away from the magazines before the latter are shifted. When therefore the lever 14 is swung clockwise, i. e., when it is raised, the segment 17 bears against the roller 18 and swings the lever 12, moving the ledge 10 out of the slot of the disc 9 and thereby release the shaft 7. At the same time the cam 19 acts against the lever 20 and swings the matrix releasing rods 21 away from the magazine, so that the shifting of the magazine can proceed. 25

According to the invention, further rocking movement of the said handle 14 causes the release and the rotary change over of the magazine entrances, and as shown this is effected by 30 means of the rod 16 attached to the lever arm 15. This rod 16 is linked by means of a stud 22 to a double lever 23 which is adapted to rock about the pivot 24 located on the lever 25, the lever 25 being itself capable of swinging about 35

a pivot 26. On the lever 25 are two abutment screws 27, 28, which limit the rocking movement of the lever 23 about its pivot 24.

Upon the shaft 26 is also mounted a toothed wheel 29 which is in mesh with a toothed wheel 30, fast on the shaft 31 upon which is also firmly secured the support 32 for the two magazine entrances 33, 34. The shaft 31 is located on a swinging arm 35 which is adapted to rock about a stationary stud 36 on the machine frame. On the same arm 35 is also located the stud 26, and a further pivot stud 37 for a double lever at one end of which is attached a spring 38 whereas the other end carries a pin 39. The latter, under the action of the spring 38 is capable of entering a recess 40 in a disc 41 positively secured upon the shaft 26. A detent 45 also adapted to engage in the recess 40, is pivotally mounted upon a shaft 24 and by a spring, not shown in the drawings, is pressed against the disc 41. A stud 42 is also provided on the machine frame to come into contact with an abutment 43 on the arm 35 in order to limit the swinging movement of the arm 35 about the stud 36.

25 The mode of operation of the present arrangement is as follows:—

When the operator desires to shift the magazines he first swings the handle 14 in order to release the shifting mechanism. When the lever 14 is raised to a certain extent the shifting shaft 7, as previously mentioned is released and the escapement rods 21 moved away from the magazine. Simultaneously, however, and by reason of the pull exerted by the rod 16, the arm 35, 35 which is held in its operative position by a very light spring 44, is rocked until the abutment 43 comes into contact with the pin 42. When the parts are in the said position, the shifting of the magazines can be effected in the usual manner 40 without adjusting the magazine entrances. If it is necessary to change-over the magazine entrances, the operator swings the lever 14 clockwise a little further. The pull exerted by the rod 16 rocks the lever 23 about its pivot 24. A 45 rotation of the lever 25 about its pivot 26 does not occur because, in consequence of the engagement of the locking pawl 45 with one of the grooves 40, it is engaged with the disc 41 and the latter is locked against rotation by the pin 39. 50 When, however, the lever 23 is rocked, the free arm of the lever bears against the pin 39 and raises the latter out of its locking position. The parts then occupy the position shown in Figure 3 in which the disc 41 has been released so that any 55 further movement will cause the locking pawl 45 and the disc 41, together with the shaft 26 and the toothed wheel 29 mounted thereon, to turn. After a quarter of a revolution, the stud 39, under the action of the spring 38, drops into the next 60 notch 40 of the disc 41; the parts are then in the position shown in Figure 4. The transmission ratio between the toothed wheel 29 and the toothed wheel 30 is such that one quarter of a revolution of toothed wheel 29 causes toothed wheel 30 to make half a revolution and thereby 65 turn the support of the magazine entrance 180 degrees. In place of the magazine entrance 33, which in Figures 2 and 3 is in the operative position, the magazine entrance 34 is brought in 70 operative position by the movement described above.

When, after shifting the magazines, the handle 14 is released, the rod 16 returns to its original position, the shaft 7 is again locked and the re-

leasing rods return into their operative position, enabling the compositor to proceed with his work.

It should be understood that the principle underlying the invention consists in arranging means common for the operations of shifting the magazines and of changing-over the magazine entrances, so that these operations can be carried out independently and in particular so that the magazines can be shifted without necessarily changing the magazine entrances. Within the 10 terms of this principle various modifications of the form of the invention described above may be introduced in order to meet different conditions and requirements which have to be fulfilled, without departing in any way from the scope 15 of the invention.

Having described my invention, I declare that what I claim and desire to secure by Letters Patent is:—

1. A typographical composing machine having 20 adjustable magazines and interchangeable magazine entrances, wherein means common to the operations of shifting the magazines and changing the matrix entrances are so arranged as to allow said operations to be effected independently irrespective of the number and relative arrangement of the magazines.

2. A typographical composing machine having 25 adjustable magazines and interchangeable magazine entrances, wherein means for unlocking the 30 magazine shifting mechanism are adapted, upon being moved beyond the extent necessary for said unlocking, to effect a change-over of the magazine entrances.

3. A typographical composing machine comprising 35 a lock for the magazine shifting mechanism, means adapted to release said lock upon being operated to a limited extent, a plurality of magazine entrances rotatable as a unit for bringing one or other into operative position in relation to the magazines, and a linkage system, connecting said magazine entrances to said releasing means, adapted to rotate the magazine entrances when said releasing means are operated beyond 40 said limited extent.

4. A typographical composing machine according to claim 3, comprising a lock for said magazine entrance unit adapted to be released upon operation of said means to the extent necessary for releasing the magazine shifting mechanism.

5. A typographical composing machine having 50 adjustable magazines and interchangeable magazine entrances, wherein common means are employed for unlocking the magazine shifting mechanism and for effecting a change-over of the 55 magazine entrances.

6. A typographical composing machine having adjustable magazines and interchangeable magazine entrances, wherein common means are employed for unlocking the magazine shifting 60 mechanism and for effecting a change-over of the magazine entrances, said means being operable to unlock the magazine shifting mechanism alone or independently when desired.

7. A typographical composing machine having 65 adjustable magazines and interchangeable magazine entrances, wherein common means are employed for unlocking the magazine shifting mechanism and for effecting a change-over of the magazine entrances, said means being capable 70 at one actuation of effecting both operations concurrently.
